ALVIN F. NYE, OF ROCHESTER, NEW YORK, ASSIGNOR OF ONE-HALF TO WILLIAM KEYEL, OF PENFIELD, NEW YORK

WINDOW SCREEN REINFORCEMENT

Application filed September 9, 1931. Serial No. 561,882.

My present invention relates to movable screens and mountings therefor, such as the roller screens that are applied to windows and porches and embodying a sliding screen body 5 guided in its lateral vertical edges and raised and lowered in the manner of a window by means of a cross rail at the bottom cooperating with the window sill when the screen is closed, and the invention has for its object to 10 reinforce and improve the attachment of the screen to this rail by way of giving additional support to the lateral edges of the screen that travel in channels or guides in the sides of the window casing or frame.

15 To these and other ends, the invention resides in certain improvements and combinations of parts, all as will be hereinafter more fully described, the novel features being pointed out in the claims at the end of the 20 specification.

In the drawings:

Fig. 1 is an inside elevation of the lower right hand corner of a window casing and sliding screen constructed in accordance with 25 and illustrating one embodiment of my invention, the screen being shown partially raised;

Fig. 2 is a similar view showing the screen lowered against the sill;

30 Fig. 3 is a horizontal cross section through the screen guide;

Fig. 4 is an enlarged fragmentary elevation of the lower right hand corner of the screen and rail alone, showing the details of 35 the reenforcing element;

Fig. 5 is an elevation of the opposite side of the reenforcing element alone;

Fig. 6 is an enlarged vertical section taken 40 on the line 6—6 of Fig. 4, and

Fig. 7 is an enlarged vertical section taken on the line 7—7 of Fig. 4.

Similar reference numerals throughout the several views indicate the same parts.

My improvements are applicable to a 45 screen mounting, such as that fully shown and described in my copending application, Serial No. 180,122, filed April 1, 1927, and in the present embodiment, I have illustrated them in connection with that disclosure, 50 showing only so much of the general struc-

ture as is necessary for an understanding of the construction and mode of operation of my improvement. As to these previous major elements, briefly described, 1 indicates the screen body having its lower edge secured 55 to a bottom rail 2 guided by bolts 3, shown in dotted lines, projecting laterally into side channels 4 secured by flanges 5 to the window casing 6. The bolt is slidably operated by means not shown to move longitudinally of 60 itself inwardly and outwardly of the channels 4 and lock and unlock with shoulders formed by depressions 7 in the bottoms of the channels to support or lock the screen at different elevations.

65 After the screen has been adjusted up and down, as desired, the expanse thereof is drawn taut laterally by catching its selvage edges 8 between clamping jaws 9 within the guide channels 4, as shown in Fig. 3. This 70 effect is accomplished through operating levers 10 which, when moved upwardly to the vertical position of Fig. 1, release the jaws 9 allowing the screen to be moved and which, when moved to the position of Fig. 2, 75 not only clamp together against the selvage edge of the screen, but, when so clamped, move inwardly within the channels 4 exerting a lateral pull on the screen at both sides. The specific action here is not necessary to 80 an understanding of the present invention.

The lower edge of the screen body is secured to the rail 2 in the manner best shown in Figs. 6 and 7. The rail is preferably hollow having the rectangular tubular form 85 shown. The upper edge of its front wall is offset rearwardly at 11 against its rear wall, which latter is doubled over or crimped down, as shown at 12, and the lower end of the screen is doubled over it in turn with its 90 raw edge inside, so that the screen body generally extends in a plane about centrally of the rail, so that there is equilibrium and there is no tendency for the latter to cock in its guide. My reenforcing member consists of 95 a doubled metal strip of yoke-like form embracing or clipped over the bottom of the screen body and indicated generally at 13, the loop at this point extending laterally beyond the selvage edge 8 and into the channel 100

4. One arm or portion 14 thereof is clamped by stamping or pressing with the raw edge of the screen between the elements 11 and 12 of the rail, while the other arm 15 extends across the screen where it emerges from the rail, and all of these parts are held securely together by a rivet 16.

The selvage edge 8 for a distance back is preferably reenforced by extra longitudinal woven screen wires 17, and a vertical upwardly extending plate 18 proceeding from about the center of the member 13 is securely affixed to such reenforced margin by means of spurs 19 struck out therefrom and bent down over the transverse wire strands. Similar spurs 20 forming serrations at the bottom edge of the plate 18 are clamped through the lower loop of the screen body and around the lower end of extension 18. The latter is additionally secured to the reenforcing body 13 by a prick punch 21 into it through the portion 14 from the rear.

This corner reenforcement I have described is simple and adds little to the cost of manufacture, yet is strong and gives general rigidity to the lower corners of the screen body which would otherwise have a tendency to become distorted interfering with the free running of the screen within their guiding channels and between the gripping jaws. The screen must project into the latter, yet the rail 2 can not do so, terminating at the mouth of the channel. The extension plate 18 is so thin that it does not interfere with the gripping of the jaws 9 and can be gripped along with the screen.

I claim as my invention:

1. In a sliding wire screen construction, the combination with a frame guide embodying a side channel member, of a wire screen having a lateral edge located within the channel, a lower rail guided in the latter, and a reenforcement for said edge projecting laterally therefrom at its bottom beyond the screen edge and into the channel to cooperate therewith as a guide, said reenforcement having a rigid vertical extension secured along said screen edge.

2. In a sliding wire screen construction, the combination with a frame guide embodying a side channel member, of a wire screen having a lateral selvage edge located, within the channel and reenforced with extra longitudinal woven wires, and a sheet metal reinforcement comprising a doubled sheet metal strip clasped about and secured to the bottom of said edge and to the rail and projecting laterally into the channel, said reinforcement having a rigid vertical extension secured by fasteners through the reenforcing wires of the selvage.

3. In a sliding wire screen construction, the combination with a frame guide embodying a side channel member, of a wire screen having a lateral selvage edge located within

the channel, a lower rail guided in the latter and having its upper edge crimped down to secure the lower edge of the screen, and a laterally projecting reenforcement caught in the crimping of the rail and having a vertical extension running longitudinally along and secured to the lateral selvage edge of the screen.
